(57) **CLAIM**

The ornamental design for a wall mounted luminaire, as shown and described.

DESCRIPTION

FIG. 1 is a perspective view of a wall mounted luminaire showing our design;

FIG. 2 is a top plan view thereof;

FIG. 3 is an enlarged left side elevational view thereof, where the right side elevational view is a mirror image of this view, and, therefore, has been omitted;

FIG. 4 is an enlarged front elevational view thereof;

FIG. 5 is another perspective view thereof, taken from a different perspective; and,

FIG. 6 is yet another perspective view thereof, taken from a different perspective.
